ATTORNEY

UNITED STATES PATENT OFFICE.

GEORGE E. SWENSON, OF PHILADELPHIA, PENNSYLVANIA, ASSIGNOR TO THE BARRETT COMPANY, A CORPORATION OF NEW JERSEY.

FLASHING-RECEPTACLE.

1,308,205.

Specification of Letters Patent.

Patented July 1, 1919.

Application filed April 8, 1918. Serial No. 227,344.

To all whom it may concern:

Be it known that I, GEORGE E. SWENSON, a citizen of the United States, residing at 4425 Clarissa street, in Philadelphia and 5 State of Pennsylvania, have invented certain new and useful Improvements in Flashing-Receptacles, of which the following is a specification.

This invention relates to the production 10 of an improved flashing receptacle or raglet, and has for its object the production and installation of such raglet in an economical, rapid and efficient manner.

In my prior patent, No. 1,254,292 granted 15 January 22, 1918, is shown an improved raggie block which has a suitably disposed groove for receiving the roof flashing. My present invention has, as one of its objects, to provide a groove in a wall made of 20 concrete similar to the groove shown in the raggie block of my prior patent above referred to.

The invention will be readily understood by reference to the accompanying drawings 25 in which:

Figure 1 is a perspective view of the flashing receptacle;

Fig. 2 is an end view of the same;

Fig. 3 is a view showing the receptacle 30 fastened to a concrete form before the concrete is poured in; and

Fig. 4 is a section showing the receptacle installed in a concrete wall.

The receptacle or raglet 1 is formed from 35 a flat sheet of suitable material such as metal of the desired length, one edge of which is bent backward to form a lip 2, and the other edge is bent to form the lip 3. The intermediate portion is so bent as to 40 form a groove or channel 4 for the reception of the flashing as will presently appear. The channel 4 is provided at its inner end with a depending flange 5 which is formed by bending the sheet as indicated.

45 After the sheet 1 has been given the desired shape it is attached in any convenient way, as by fasteners 6, to the inside of one of the walls of the concrete form 7 and the concrete to form the wall is poured in.

50 After the concrete has set, the form 7 is removed and the ends of the fasteners 6 are bent to the side or clipped off flush with the surface of the sheet 1.

A cant strip 8 may be provided as de-

scribed in my prior patent and as illustrated 55 in Fig. 4. The flashing, or the roof covering itself may be laid along the cant strip 8 and into the groove 4 in a manner readily understood by those skilled in the art.

It is thus seen that by my invention a 60 groove is readily provided in the wall for receiving the flashing in such a manner that there is no danger of leakage and at the same time providing for expansion and contraction of the roofing material. 65

It is not necessary that the sheet 1 be made of such material that it will not be affected by the corroding influences of the weather, because after the concrete once hardens the sheet 1 may disintegrate 70 entirely without in any way interfering with the installation of the flashing.

75 Preferably the receptacle should be made of material of such strength and rigidity that it will not sag when the concrete is poured in. If desired, straps of metal 9 may be laid at intervals with their bent ends 10 hooked over the lip 2 and their bent ends 11 hooked over the flange 5 as indicated in Fig. 3 to maintain the middle portion 80 4 in place before the cement sets.

I am aware that prior to my invention forms have been provided in concrete structures which forms are subsequently removed to leave grooves and apertures of 85 proper shape and size for different purposes. The removal of these forms entails considerable difficulty and expense and often results in chipping the concrete, thus leaving the grooves in a rough and unsatisfactory condition. By my invention I 90 avoid these objectionable features and provide a groove which is readily adapted for the reception of a roof flashing.

95 The lips 2, 3 and the flange 5 assure the retention of the receptacle in place in the concrete while the form 7 is being removed, and the slope of the groove 4 avoids all danger of water creeping up its sides and finding its way behind the flashing. 100

What I claim is:

1. A concrete wall having a narrow, upwardly and inwardly inclined groove of substantially parallel sides lined on both sides with a thin sheet of smooth material, 105 said sheet being anchored in said wall at the edges and near the central portion of said sheet.

2. A flashing receptacle consisting of a sheet of material so bent as to form upstanding portions and an intermediate inclined portion, said inclined portion having substantially parallel sides, and being inclined substantially 45° to the upstanding portion.
3. A flashing receptacle consisting of a sheet of material so bent as to form upstanding portions and an intermediate inclined portion, said upstanding portions having lips thereon and said inclined portion having a flange thereon.
4. A flashing receptacle consisting of a sheet of material so bent as to form upstanding portions and an intermediate inclined portion, said upstanding portions having lips thereon and said inclined portion having a flange thereon, the plane of said flange being substantially parallel to one of said lips and perpendicular to the other.
5. A flashing receptacle consisting of a single piece of sheet metal having a flat face and a narrow inclined groove intermediate the edges of said face.
6. A flashing receptacle consisting of a single piece of sheet metal forming a flat face and a groove inclined approximately 45° to said face, said face having lips thereon, and said groove having a flange thereon.
7. A flashing receptacle consisting of a single piece of sheet metal forming a flat face and an inclined groove, said face having lips thereon, said groove having a flange thereon, and a support extending from one of said lips to said flange.

In testimony whereof I affix my signature.

GEORGE E. SWENSON.
